Edward J. Miller

UNITED STATES PATENT OFFICE

ALBERT RAPHAEL, OF BROOKLYN, NEW YORK

FLEXIBLE REAMER FOR CABLE TERMINALS AND THE LIKE

Application filed November 12, 1931. Serial No. 574,489.

This invention relates to new and useful improvements in a flexible reamer for cable terminals and the like.

The invention has for an object the construction of a flexible reamer which is adapted to clean out the inner face of a terminal and the like in an efficient manner.

As a still further object of this invention it is proposed to arrange resilient cutting 10 elements on the device for engaging within the cable terminal or the like and accomplishing cleaning upon turning back and forth.

As a still further object, it is contemplated to construct the cutting element with a diamond-shaped cutting edge so that the reamer may be turned in either direction during cleaning. Furthermore, the cutting element may be arranged with straight sides 20 parallel to the axis of the reamer or at an inclination thereto for cleaning straight or tapered openings.

As a still further object of this invention it is proposed to arrange the reamer with a 25 barrel portion having a reduced front end for receiving a cap, and a plurality of longitudinal slots formed in from the shoulder of the reduced end for accommodating the cutting elements thereof.

Another one of the objects of this invention is the provision of means for limiting the inward motion of the cutting elements to variable distances as desired.

Other objects of this invention are the 35 construction of a device of the class mentioned which is of simple, durable construction, dependable in use and efficient in action, and which can be manufactured and sold at a reasonable cost.

For further comprehension of the invention, and of the objects and advantages thereof, reference will be had to the following description and accompanying drawing, and to the appended claims in which the 45 various novel features of the invention are more particularly set forth.

In the accompanying drawing forming a material part of this disclosure:—

Fig. 1 is a perspective view of a reamer 50 constructed according to this invention.

Fig. 2 is a side elevational view of one of the cutting elements thereof.

Fig. 3 is a fragmentary enlarged sectional view taken on the line 3—3 of Fig. 1.

Fig. 4 is a view similar to Fig. 2 but illustrating another form of cutting element.

Fig. 5 is a fragmentary central longitudinal sectional view of a reamer constructed according to a modified form of the invention.

Fig. 6 is a perspective view of a cable terminal which may be cleaned by the reamer.

The flexible reamer consists of a barrel 10 having a reduced end 11 and a plurality of longitudinal slots 12 formed in from the shoulder produced by the reduced end 11. Each of these slots has its inner end reduced, indicated by reference number 13, so as to form an overhanging ledge 14. A cap 15 is threadedly engaged upon the reduced end 11 and is formed with a circular flange 16 directed towards the ledge 14. Cutting elements 17 are engaged within the slots 12 and have reduced ends 18 adapted to engage beneath the ledges 14 and the flange 16. Resilient means are provided for selectively urging each of the cutting elements 19 outwards and comprises bowed springs 19 located within the slots 12 and acting between the bases of the slots and the inner edge of the cutting element.

The barrel 10 is equipped with a handle 20 to facilitate the operation of the reamer. The cap 15 is formed with knurlings 21. The cutting elements 17 are shown in the form of blades having diamond point cutting edges 22 allowing the reamer to be turned either way. The cutting blades shown in Figs. 1 to 3 inclusive have their cutting edges at an inclination to their inner sides so that when this type of blade is used a tapered opening may be cleaned.

In Fig. 4 another form of blade has been illustrated in which the cutting edge is parallel to the bottom side for the purpose of reaming a straight hole. The cutting element may be formed from a stone, abrasive or the like material.

In Fig. 5 another modification of the in-

vention has been disclosed in which provision has been made for locking the cutting elements against depression whenever desired. A flexible reamer has a barrel 23 formed with a plurality of longitudinal slots 24 around its periphery and extend inward from one end thereof. A cap 25 is threadedly engaged on the end of the barrel 23 and has its inner side 26 of substantially frusto-conical form. A ring 27 is rotative upon the barrel 23 and has the side 28 nearest the end of the barrel formed of substantially frusto-conical shape.

A means is provided for limiting the sliding of the ring 27 to a position in which cutting elements 29 resiliently projecting from the slots 24 are either free or latched. This means comprises a cam cut 33 formed on the outer side of the ring 27 and engagable by a stationary pin 34 projecting from the barrel 23. Springs 35 are located within the slots 24 and serve to urge the cutting elements 29 outwards. Each of the cutting elements 29 have bottom projecting ends 36 engaging respectively within the cap 25 and the ring 27. As shown in Fig. 5, the cutting elements 29 are held against depression. The ring 27 may be turned and simultaneously moved backwards as permitted by the cutout 33, whereupon the cutting elements 29 may be depressed against the resiliency of the springs 35.

In Fig. 6, a cable terminal 30 has been illustrated which is shown fixed upon a cable 31. This cable terminal has a central opening 32 which is formed slightly tapered. The reamer may be engaged within the opening and turned backwards and forwards so as to clean the opening to insure proper contact upon the terminal of a battery. The terminal of a battery in operation corrodes and a deposit forms upon it and upon the cable terminal which must be cleaned to insure proper electrical contact. The reamer may be used for a multitude of purposes. It will adapt itself readily to various tapered openings and straight openings due to the flexibility of the mounting of the blades.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit or the scope of the appended claims.

Having thus described my invention, what I claim as new, and desire to secure by United States Letters Patent is:—

1. A flexible reamer for cable terminals and the like, comprising a barrel formed with a plurality of longitudinal slots around its periphery, a cap threadedly engaged up-

on said barrel and having its inner side of substantially frusto-conical form, a ring rotative on said barrel and having the side nearest the said cap of substantially frusto-conical form, cutting elements within said slots and having both ends formed with acute notches adapted to be engaged in extended positions by said frusto-conical sides and having reduced ends extending respectively beneath the sides of said cap and ring, resilient means urging said cutting elements outwards, and means for limiting longitudinal sliding of said ring within pre-determined limits wherein the frusto-conical portions of the cap and ring engaged said acute notches for holding the cutting elements extended or wherein the cap and ring limit extension of said reduced ends only so that the cutting elements may be depressed.

2. A flexible reamer for cable terminals and the like, comprising a barrel formed with a plurality of longitudinal slots around its periphery and extended in from one end a cap threadedly engaged upon said end and having its inner side of substantially frusto-conical form, a ring rotative on said barrel and having the sides nearest the end of the barrel of substantially frusto-conical form, cutting elements within said slots and having sides converging and adapted to be engaged in extended position by said frusto-conical sides and having reduced ends extending respectively beneath the sides of said cap and ring, resilient means urging said cutting elements outwards, and means for limiting longitudinal sliding of said ring with pre-determined limits for firmly holding the cutting elements extended when desired, comprising a pin projecting from said barrel and engaging in a cam cutaway in the edge of said ring.

3. A flexible reamer for cable terminals and the like, comprising a barrel with a plurality of longitudinal slots around the periphery thereof, a ring-shaped element on said barrel extending over one of the ends of said slots, another ring-shaped element on said barrel and extending over the other ends of said slots, cutting elements in said slots and having ends engaging beneath said ring-shaped elements, resilient means within said slots urging said cutting elements resiliently into extended positions, said ring-shaped elements being slightly longitudinally adjustable relative to each other and in the remote position serving as limits for said ends of the cutting elements for preventing their depressions.

4. A flexible reamer for cable terminals and the like, comprising a member formed with a plurality of longitudinal slots, a cap threadedly engaged upon said member and having its inner side of substantially frusto-conical form, a member on said member and having the sides nearest said cap

of substantially frusto-conical form, cutting elements within said slots and having notched sides adapted to be engaged in extended positions by said frusto-conical sides and furthermore having reduced ends extending respectively beneath the sides of said cap and member, resilient means urging said cut-

ting elements outwards, and means for limiting longitudinal sliding of one of said members within predetermined limits, comprising a pin projecting from one of said members and engaging in a cam cutout in the other of said members.

ALBERT RAPHAEL.
